UNITED STATES PATENT OFFICE.

DANIEL S. BEARD, OF WAYNESBORO, PENNSYLVANIA, ASSIGNOR TO THE GEISER MANUFACTURING COMPANY, OF WAYNESBORO, PENNSYLVANIA.

HAY-PRESS.

957,538.

Specification of Letters Patent.

Patented May 10, 1910.

Application filed June 1, 1909. Serial No. 499,425.

To all whom it may concern:

Be it known that I, DANIEL S. BEARD, a citizen of the United States, residing at Waynesboro, in the county of Franklin and State of Pennsylvania, have invented certain new and useful Improvements in Hay-Presses; and I do hereby declare the following to be a full, clear, and exact description of the invention, such as will enable others skilled in the art to which it appertains to make and use the same.

This invention relates to presses for baling hay and other similar material; and it consists in the novel construction and combination of the parts used for guiding and dropping the blocks into the press-chamber and for folding the hay behind the press-plunger.

In the drawings, Figure 1 is a side view of a portion of the press showing the novel 20 folder and block-dropper. Fig. 2 is an end view of the same showing a portion of the press in section on the line $x-x$ in Fig. 1. Fig. 3 is a section through the folder taken on the line $y-y$ in Fig. 1. Fig. 4 is a plan 25 view of the parts shown in Fig. 1, with the block-dropper removed.

A is a portion of the press-chamber of a hay-press of any approved construction, and B is the feed-opening at the top thereof. 30 The press is provided with angle-shaped bars a' at its upper part, and the horizontal flanges of these bars are cut away at the sides of the feed-opening B. Flat bars b are secured to the sides of the vertical 35 flanges of the bars a' at the sides of the feed-opening B to reinforce them at this point, and to afford a free passage for the hay. The press-plunger, not shown, slides under the feed-opening and compresses the 40 hay in the press-chamber when moved rearwardly in the direction of the arrow in Fig. 1. A folder-roller C is provided at the rear part of the feed-opening to prevent the hay from jamming between the top of 45 the press-chamber and the press-plunger.

D are brackets secured to the press and provided with guide-pockets d . These guide-pockets are preferably circular, but they may be oval if desired. The roller C is provided with a shaft c which is mounted loosely in the guide-pockets d , said pockets being about four times as large in diameter as the shaft c , so that the roller C may be free to move in all directions within the

limits imposed on it by the pockets. The 55 roller C is preferably made of a thin metallic shell secured on heads c' which are secured to the end portions of the shaft c . The bottoms of the pockets d have openings to admit the shaft c . These openings are 60 closed by the vertical flanges of the bars a' and the bars b , said parts having curved notches d' cut in them to conform to the shape of the pockets d and to complete their bottom portions.

E are vertical guard-plates which project around the upper parts of the guide-pockets d ; and e are curved flanges on the front parts of the plates E which project over the ends of the roller C and prevent the hay 70 from catching between the ends of the roller and the guide-pockets.

F is the top of the press-chamber A, formed of a thin metallic plate and having an up-turned flange f at its end behind the 75 guide-pockets. The flange f curves gently into the plate F so that a sharp corner is not formed, and a packing-piece g and an angle-shaped bar g' are secured to the said plate and its flange to strengthen them.

H are springs having their rear end portions adjustably secured in brackets h , which are bolted to the press-chamber. The front end portions of the springs H bear downwardly on the roller C.

When the press-plunger is moved so as to force the hay rearwardly into the press-chamber, the roller C rolls and slides about to suit the hay, and enables the hay to be folded into the press-chamber below the 90 roller C without catching or jamming.

I are channel-shaped bars which form the ends of the block-dropper. These bars form guides for the blocks which are slidable in their channels. Retaining springs i are secured in the lower parts of the channels for preventing the blocks from sliding through the guide-channels unless forcibly pressed down in them.

J and J' are cross-bars which couple the 100 bars I together, and j are angle-shaped arms secured to the lower crossbar J. The arms j are cranked and offset to one side and are pivoted to the brackets D by pins j' , but they may be pivoted to any other similar supports.

K is a socket secured to the middle parts of the crossbars, and k is an operating han-

dle or lever which engages with the socket K, and which may be removed therefrom when not required in use.

L is a stop secured to the top of the press 5 to prevent the block-dropper from being tilted too far rearwardly. When the block-dropper is tilted rearwardly the socket K strikes the stop L.

A block is placed between the bars I when 10 tilted rearwardly, and the block and the block-dropper are then moved to the vertical position shown in Fig. 1 by means of the handle k. The mechanism of the press then forces the block downwardly in the guide-bars I into the press-chamber in any approved manner.

What I claim is:

1. The combination, with a press-chamber provided with a feed-opening, of brackets 20 provided with guide-pockets and secured to the said chamber at the rear part of the feed-opening, a folder-roller provided with a shaft having its end portions free to move about in the said pockets, and springs which 25 press the said roller downwardly in the said feed-opening.

2. The combination, with a press-chamber provided with a feed-opening, of brackets 30 provided with guide-pockets and secured to the said chamber at the rear part of the feed-opening, said brackets being also provided with vertical guard-plates at their upper parts and having laterally projecting flanges at the front parts of the said guard-plates, a 35 folder-roller provided with a shaft having its end portions free to move about in the said pockets, and springs which press the

said roller downwardly in the said feed-opening.

3. The combination, with a press-chamber 40 provided with a feed-opening and having bars at its sides, of brackets provided with guide-pockets and secured to the said chamber at the rear part of the feed-opening, the said pockets having openings at their bottoms 45 which are closed by the said bars, a folder-roller provided with a shaft having its end portions free to move about in the said pockets, and springs which press the said roller downwardly in the said feed-opening.

4. The combination, with a press-chamber, of a block-dropper comprising two channel-shaped guides and two crossbars secured to the said guides, and two cranked and offset arms secured at one end to the end portions 55 of the lower crossbar and having their other end portions pivoted to the press-chamber.

5. The combination, with a press-chamber, of a block-dropper comprising two channel-shaped guides and two crossbars secured to 60 the said guides, two cranked and offset arms secured to the end portions of the lower crossbar and pivoted to the press-chamber, a socket secured to the middle portions of the 65 said crossbars and bracing them together, and a handle projecting from the said socket.

In testimony whereof I have affixed my signature in the presence of two witnesses.

DANIEL S. BEARD.

Witnesses:

G. A. ANDERSON,
J. STORER PRICE.
